UNITED STATES PATENT OFFICE.

CLARENCE B. HAYNES, OF CAMDEN, NEW JERSEY, ASSIGNOR OF TWENTY-TWO AND ONE-HALF ONE-HUNDREDTHS TO CHARLES A. RICHARDSON, OF HADDONFIELD, NEW JERSEY, TWENTY-TWO AND ONE-HALF ONE-HUNDREDTHS TO MAX LIVERIGHT, OF PHILADELPHIA, PENNSYLVANIA, AND TEN ONE-HUNDREDTHS TO WILLIAM K. B. RICHARDSON, OF HADDONFIELD, NEW JERSEY.

AIR-MOISTENER.

1,143,962.

Specification of Letters Patent. Patented June 22, 1915.

Application filed January 29, 1914. Serial No. 815,301.

To all whom it may concern:

Be it known that I, CLARENCE B. HAYNES, a citizen of the United States, residing at Camden, county of Camden, State of New Jersey, have invented a new and useful Air-Moistener, of which the following is a specification.

My invention consists of an improved device for moistening the air-supply to the carbureters of internal combustion engines, in which the moistening water is fed to a helical body of absorbent material through which the air to be moistened passes.

It further consists of other novel features of construction, all as will be herein-after fully set forth.

The annexed drawings and the following description set forth in detail one mechanical form embodying the invention, such detail construction being but one of various mechanical forms in which the principle of the invention may be used.

In said annexed drawings—Figure 1 represents a top plan view of my improved moistening device. Fig. 2 represents a side elevation of the same. Fig. 3 represents a section of the device. Fig. 4 represents a perspective view of a form of nipple which may be employed.

Similar numerals of reference indicate corresponding parts in the figures.

Referring to the drawings, the reference numeral 1 indicates a substantially cylindrical casing which constitutes a moistening chamber and having its lower end closed by a screw-cap, 2, and having a dome-shaped reservoir, 3, secured upon its upper end, the top of which reservoir has a nipple, 4, or similar connection to which a pipe or hose or similar supply means for the moistening water may be connected.

A flanged and apertured plug, 24, is screwed into a central opening in the top of the casing, and the upper end, 5, of a helix, 6, or similar tortuous body of felt or similar absorbent material fits in the aperture of said plug. A helix-core, 7, of metal wire or similar material, passes through the axis of the absorbent cord which forms the helix, and the upper end of such core is screw-threaded, at 8, and has a nipple, 9, secured upon it and inclosing

the end of the absorbent cord and retained by a nut, 10, screwed upon the threaded end of the core. The lower end of the core is secured in the center of the bottom cap by a nut, 11, screwed upon it. A neck, 12, is formed upon the side of the casing, and a strainer, 13, is clamped against the end of said neck by a coupling-nut, 14, and a nipple, 15, which is adapted to be connected to the intake of an internal combustion engine. A valve-chamber, 16, extends laterally from the upper portion of the casing and has an inwardly facing seat, 17, upon which an inwardly opening valve, 18, is seated to control an air intake, 19, and having springs, 20 and 21, and adjusting nuts, 22 and 23, for controlling it.

In practice, the casing is connected to the gas intake or manifold of an internal combustion engine, and the reservoir is connected to a source of water. The water in the reservoir will be absorbed by the upper end of the absorbent helix and will gradually soak the entire helix, and whenever the engine draws in air and oil or gasoline or whatever fuel through the carbureter, the air will pass through the air intake and through the absorbent helix, absorbing moisture from the latter and passing to the intake where the moist air will mix with the fuel and thus produce a superior explosive mixture.

The absorbent helix affords a large evaporating surface while occupying comparatively small space, and the water will be aided by gravity in being absorbed in the helix, as it surrounds the upper end of the latter, so that the helix will be saturated and will amply moisten the air. The wire-core of the helix will support the same and retain its form, and the projecting ends of the core will provide convenient and solid means of attachment and support for the helix. The strainer in the passage from the moistening chamber to the carbureter will prevent any solids which might enter with the air from passing into the engine, and will also break up any globules of water which might be formed from oversaturation of the helix.

Other modes of applying the principle of my invention may be employed for the mode

herein explained. Change may therefore be made as regards the mechanism thus disclosed, provided the principles of construction set forth respectively, in the following 5 claims are employed.

Having thus described my invention, what I claim as new and desire to secure by Letters Patent, is:—

1. An air moistener, comprising a casing 10 forming an air moistening chamber having an air inlet and an air outlet and a liquid reservoir, adjacent thereto, having an aperture forming a communication with the chamber, and a body of absorbent material 15 having a portion thereof fitting and closing the aperture to insure that moisture is fed only by capillary action and having one end secured in the chamber, the other end extending into the liquid in the reservoir, 20 whereby the body will absorb liquid in the

reservoir and such liquid evaporate in the chamber.

2. An air moistener comprising a casing forming an air moistening chamber having an air inlet and an air outlet and a liquid 25 reservoir, adjacent thereto, having an aperture forming a communication with the chamber, means for feeding the liquid to the air moistening chamber by capillary action only, said means including a plurality 30 of coils situated in said moistening chamber, and a supporting member having its ends suitably mounted and engaging said body throughout its extent to hold the coils in spaced relation to each other and to the 35 casing.

CLARENCE B. HAYNES.
